(No Model.)

C. C. WRENSHALL.
COMBINATION TIE PLATE AND RAIL CLIP.

No. 450,305.

Patented Apr. 14, 1891.

UNITED STATES PATENT OFFICE.

CHARLES C. WRENSHALL, OF ANNISTON, ALABAMA.

COMBINATION TIE-PLATE AND RAIL-CLIP.

SPECIFICATION forming part of Letters Patent No. 450,305, dated April 14, 1891.

Application filed May 31, 1890. Serial No. 353,729. (No model.)

To all whom it may concern:

Be it known that I, CHARLES C. WREN-
SHALL, of Anniston, in the county of Calhoun
and State of Alabama, have invented certain
5 Improvements in Combination Tie-Plates and
Rail-Clips, of which the following is a speci-
fication.

My invention relates to improvements in
combined tie-plates and rail-clips for railway-
10 tracks, and the object I have in view is to
prevent the spreading of the railway-rails oc-
casioned by their outer flanges or bases be-
coming embedded in the cross-ties by the
pressure exerted by the passing trains. The
15 force thus exerted usually causes the rails to
assume positions out of the normal perpen-
dicular line. This is especially the case where
curves occur in the track where the pressure
and weight of the fast traffic are exerted at an
20 angle and tends to force the heads of the rails
outward and to crush the outer flanges of the
rails into the cross-ties. Braces have been
used to support the heads of the rails and
prevent them from being thus forced out-
25 ward; but in order that they may be effectual
the braces must be of sufficient strength and
solidity to support the whole weight brought
to bear upon them or the edges of the braces
next the rails will become embedded in the
30 cross-ties, and thus fail to support the rails.
Another disadvantage in this manner of brac-
ing is that the point at which the rails are
most liable to become tilted or forced outward
is at the connecting-joint, and it is impossible
35 to apply these braces at this point on account
of their interference with the plates connect-
ing the rails together, so that with these de-
vices the weakest portions of the tracks are
left without support.

40 With my invention the rails are held firmly
and squarely upon their base and sufficient
surfaces are covered by the supporting-plates
to prevent any portion of the plates becom-
ing embedded, even when soft-wood cross-ties
45 are used. I also hold the rails at the joints
without interfering with the connecting-
plates and secure the tie-plates and rails firmly
together and prevent any rattle or loose mo-
tion between them.

50 In the accompanying drawings, forming a
part of this specification, Figure 1 is a sec-
tional elevation of my improved tie-plate,
showing the rail in position thereon with the

clips, bolts, and fillers. Fig. 2 is a plan view
of the same, one of the nuts and clips and fill- 55
ers being removed, showing the opening in
the tie-plates adapted to receive the bolt and
the angle-piece of the clip. Fig. 3 is an ele-
vation of the clip, showing the shoulders
thereon. Fig. 4 is a detail of one of the fill- 60
ers. Fig. 5 shows the screw-socket wrench
used for screwing down the bolts into the
ties. Fig. 6 shows a modification thereof.
Fig. 7 illustrates the manner of cutting out
the sides of the bolts and the inside of the 65
modified form of wrench shown in Fig. 6.

In the drawings, 2 represents the tie-plate,
preferably formed of sheet metal, although I
do not confine myself to this material, having
a plane lower surface of sufficient area in 70
contact with the upper surface of the cross-
tie to distribute the weight brought to bear
upon the rail and avoid the liability of any
portion of said plate becoming embedded
in the cross-tie. The rail 3 is placed upon 75
the upper surface of this tie-plate 2, and is
firmly held in position by the clips 4 and
5. As shown, these clips are provided
with the smaller angle portion 6, adapted to
be inserted through the openings 7 in the 80
tie-plate 2, the shoulders 8 upon the clips be-
ing prevented from coming in contact with
the upper surface of the tie-plate by a filler
9 of sufficient thickness. The bolts 10 are
screwed down into the tie, as shown, a hole 85
being first bored out in the tie to receive them.
I preferably provide a grip-thread 11 upon
the upper end of these bolts 10 and the stand-
ard threads, as shown, upon the lower ends 12,
the portion 13 between them being unthreaded. 90
The bolt 10 is screwed down until this un-
threaded portion comes into the tie. The
plate is then placed in position, the varying
distances between the bolts 10 in the ties be-
ing accommodated by the slotted portions 14 95
of the openings 7 in the tie-plate. The rail
is now placed in position upon the tie-plate
and the fillers 9 are placed upon the bolts,
being preferably made so as to just fill in the
spaces between the bolt and the edge of the 100
rail and the angle portion of the clip and the
edge of the rail. The clips 4 and 5 are slipped
over the upper ends of the bolts 10 and the an-
gle portion 6 inserted through the openings
7 in the tie-plate and the lock-nuts 15 screwed 105
down upon the clips to bring them firmly

against the upper surface of the base of the rail.

I am aware that bolts with heads formed thereon have been used for clamping rails and cross-ties together. In such cases it becomes necessary to turn the bolt in the cross-tie in order to release the rail. This becomes impracticable, either from the impossibility of turning the bolt after it becomes corroded or from the wearing away of the soft material of the tie by the contact of the bolt-threads.

It will be seen that with my invention I secure the bolts in the cross-tie and the clamping is done by the nuts 15 without disturbing the bolts.

In order to force the screw-bolt 10 to its proper position in the cross-tie, I prefer to provide a socket crank or wrench 16. (Shown in Fig. 5, and in a modified form in Fig. 6.)

20 The socket 17 is preferably provided with an internal screw-thread corresponding to the screw-thread upon the bolt 10. The bolt 10 is first inserted in this socket until the end of the bolt strikes against the upper wall.

25 The wrench is then used as an ordinary bit and brace and the bolt 10 is screwed into the opening prepared for it in the cross-tie without injury to the threads upon the said bolt.

In the modified form shown in Figs. 6 and 30 7 the socket of the wrench is given the form shown at 18, Fig. 7, and is adapted to slip down over the upper part of the bolt, which in this case would be provided with the grip-thread 11 upon the unthreaded portion of the

35 bolt and there engaged with the corresponding notches 19 in the said unthreaded portion, when the bolt may be screwed down. It will be seen that the clips 4 and 5 lie at an angle with the rail and the plate, the heels of the clips resting

40 on the filler upon the tie-plate, their inner ends resting upon and bearing against the upper surfaces of the rail-base, thus serving, when subjected to the strain of the bolts

45 10, to hold the rail firmly in place upon the tie-plate, and also to hold the plate itself in correct position, binding the whole to the cross-tie. To insure the rail keeping its position

50 against movement laterally I provide the angle-pieces 6 upon the several clips that project through the openings in the plate 2, by means of which the clips and bolts are prevented from being pushed outwardly.

Having thus described my invention, I claim as new and desire to secure by Letters Patent—

1. The combination of a railway-rail, its tie, a plate upon said tie supporting said rail, spring-clips overlapping the base of the rail, securing-bolts passing through said plate and 60 clips, and fillers arranged underneath said clips and between said bolts and the edges of the rail-base, substantially as described.

2. The combination, with a railway-rail and its tie, of a tie-plate having openings 7 and 65 slots 14, spring-clips engaging the base of the rail, bolts passed through said clips and said slots 14 and screwed into the tie, fillers 9 be-

tween said plate and said clips, and lock-nuts 15 upon said bolts, substantially as described.

3. The combination, with a railway-rail, its 70 tie and tie-plate, of spring-clips bearing upon the upper surface of the rail-base and having heels projecting through openings in the tie-plate, fillers between said clips and said plate, double-threaded bolts passing through said 75 clips and plate and screwed into said tie, and nuts upon said bolts, substantially as described.

4. The combination, with a railway-rail, its tie, and a perforated tie-plate, of a spring-clip 80 having its heel entering an opening in said plate and its body overlapping the base of the rail, a filler interposed between the edge of the rail-base and the heel of the clip, and a bolt passing through said plate and clip and 85 securing said clip upon said rail and filler, substantially as described.

5. The combination, with a railway-rail, its tie, and tie-plate, of slotted openings through 90 said plate, bolts passing through said openings into said tie, fillers between said bolts and the edges of the rail-base, clips bearing upon said fillers and rail-base, and nuts threaded upon said bolts and bearing upon said clips.

95 6. The combination, with a railway-rail and its tie, of a tie-plate having openings therethrough, bolts passed through said openings into said tie and provided with a common standard thread upon the lower end, and a grip-thread upon the upper end, and also provided with an unthreaded portion intermediate of said threads, fillers arranged upon said plate between said bolts and rail, spring-clips arranged upon said fillers and overlapping the 100 rail-base, and having heels entering openings in the tie-plate, and lock-nuts upon the upper end of said bolts bearing upon said clips, substantially as described.

7. A railway-rail fastening comprising, in 110 combination, a perforated tie-plate, a spring-clip overlapping the base of the rail, a down-turned heel upon said clip engaging with said tie-plate, a filler arranged between the heel of the clip and the base of the rail, and means 115 for securing said clip upon said filler and base, substantially as described.

8. In a railway-rail fastening, the combination of a perforated tie-plate, a bolt extending from the tie through the opening in said plate, a filler upon said plate, a spring-clip upon said filler and the base of the rail, having an opening to receive said bolt and an angle portion extending downward through the opening in said plate, and a locking-nut 125 threaded upon said bolt and bearing upon said clip, substantially as described.

In testimony whereof I hereunto set my hand this 2d day of April, 1890.

CHARLES C. WRENSHALL.

In presence of—

C. H. CANFIELD,
W. C. METCALF.
